UNITED STATES PATENT OFFICE

HENRY F. KEIL, OF SCARSDALE, NEW YORK, ASSIGNOR TO FRANCIS KEIL & SON, INC.,
A CORPORATION OF NEW YORK

SUPPORT FOR SHELVES AND THE LIKE

Application filed February 10, 1928. Serial No. 253,323.

This invention relates to supports for shelves and the like. One of the objects thereof is to provide an adjustable support of the above nature which is securely held in the position to which it is adjusted. Another object is to provide a construction of the above nature which is held firmly against displacement by an accidental blow thereon and against tendencies to be displaced when the shelf is being removed or placed in position. Another object is to provide a construction of the above nature which is simple and thoroughly dependable. Another object is to provide a construction of the above nature which is inexpensive to manufacture. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

25 In the accompanying drawings which show one or more of the various possible embodiments of the features of this invention,

Figure 1 is a perspective view showing two of the supports and a shelf carried thereby;

30 Figure 2 is a section taken substantially as indicated by the line 2—2 in Figure 3;

Figure 3 is a vertical section through the shelf and support;

Figure 4 is a detailed view of a part of the 35 supporting structure;

Figure 5 is a sectional view of a construction at the outer end of the support.

Figure 6 is a top view of the parts shown in Figure 5;

40 Figure 7 is a detail view showing a modified construction in one part of the structure, and

Figure 8 is a rear view of the parts shown in Figure 7.

45 Similar reference characters refer to similar parts throughout the several views of the drawings.

Referring now to the drawings in detail, there is shown a supporting member 10 of 50 elongated shape which is adapted to be se-

cured in upright or vertical position against a wall, such as the wall 11, which may be, for example, the rear wall of a display case or the like. The member 10 is preferably stamped from sheet metal and is of channel shape or U-shaped, having side flanges 10a and 10b, the edges of which rest against the wall 11 and which hold the front wall of the member outwardly in spaced relation to the surface of the wall against which it is secured. As shown herein, the member 10 is provided with a hole adjacent each end to receive securing devices such as screws 12 for fastening the member in place.

In the front wall of the member 10 are a plurality of spaced openings or slots which may be said to be of keyhole shape, the slots having relatively wide upper portions and relatively narrow lower portions. Exterior of the member 10 is a supporting member having two parts bent substantially at right angles to each other, a vertical part 13 and an outwardly horizontally extending part 14. The part 13 is adapted to rest against the outer surface of the member 10 and the outwardly projecting part 14 supports the shelf member 15 or other device to be supported by this construction. As shown in Figure 1, the outer end of the part 14 has preferably an upturned lip 14a to hold the shelf member 15 against forward displacement. Extending downwardly and rearwardly from adjacent the outer end of the part 14 is a bracing rod 16. As shown in Figure 3 the end of the rod 16 passes through an opening in the part 13 and is threaded, having thereon a nut 17 exterior of the member 13. The rod 16 thus braces the supporting part 14 and, by means of the nut 17, the shelf may be adjusted so that it is horizontal from front to rear.

In the part 13 above the opening through which the rod 16 passes is another opening through which passes a bolt 18. This bolt has at the rear end thereof a head 19 which is of such size that it will pass through the relatively large upper end portion 20 of the keyhole slot in the member 10 but will not pass through the relatively narrow lower part of the slot. Also, as shown in Figure 3,

the bolt 18 has a part 21 adjacent to the head 19 which is of larger diameter than the shank of the bolt and smaller than the head. Also, this part 21 of the bolt is preferably tapered, increasing in diameter toward the head 19.

Referring to Figure 2, the lower relatively narrow portion 22 of the keyhole slot has its sides notched or cut away at 23 and 24 so that the relatively narrow portion is somewhat widened at this part. The part 23-24 of the slot is of a size to receive the tapered portion 21 of the bolt, while the part 22 of the slot is of smaller width, permitting easy passage of the shank of the bolt but not of sufficient width for passage of the part 21. The slot thus comprises three separate portions, the relatively wide portion 20 of a size to accommodate the head 19 of the bolt, the lower part 23-24 to receive the part 21 of the bolt, and the intermediate still narrower part 22.

In mounting this shelf support in position, the member 10 is first secured against the wall; the bolt 18 is inserted through the opening therefor in the part 13 and the nut 25 is threaded loosely upon the bolt. Thereupon, the bolt head 19 is inserted through the upper relatively wide portion 20 of one of the key-hole slots, the slot selected depending upon the height at which the shelf is desired to be supported. The head 19 having been inserted into the keyhole slot, and the nut 25 being loose, the member 13-14 is allowed to slip downwardly, the shank of the bolt 18 moving through the part 22 of the slot until it reaches the lower portion 23-24. The nut 25 is now tightened up to draw the part 21 into the slot portion 23-24, the parts being preferably so proportioned that the tapered part 21 wedges to some extent against the sides 23 and 24. The nut 25 having been tightened and the part 21 thereby drawn into the slot portion 23-24, the bracket member 13-14 is effectively locked against upward movement until the nut 25 is again loosened to permit rearward movement of the bolt 18. The narrowed portion 22 of the slot forms a positive blocking against upward sliding of the bolt and bracket member. When the shelf member 15 is being removed for cleaning, or if the parts 14 or 16 are accidentally struck from below, there is no danger of the bracket member 13-14 being loosened.

It may be noted that the slots in the member 10 are so spaced that, when the bolt 18 is in the top slot, the end 16a of the bracing member 16 takes into the middle slot; when the bolt 18 is in the middle slot the end 16a takes into the bottom slot, as is illustrated in the drawings. About the opening in the part 13 through which the bolt 18 passes the metal is preferably forced outwardly as shown at 13a in Figure 3. As shown in Figure 4, the opening 13b through this part 13a is squared and, as shown in Figure 4, the shank of the bolt 18 is correspondingly squared or flat-

tened. The engagement of the squared shank of the bolt with the squared opening 13b holds the bolt against rotation as the nut 25 is turned to loosen or tighten the support.

As has been mentioned earlier herein, the outer end of the arm 14 has an upwardly bent portion 14a which holds the shelf member 15 from sliding forwardly. Referring to Figure 3, positioned upon this portion 14a of the arm is a member 26 for the purpose of preventing the shelf 15 from being accidentally lifted upwardly. This member 26, which is shown in detail in Figures 5 and 6, is preferably stamped from sheet metal and comprises a flat portion which overlaps the edge 80 of the shelf member 15, and a downwardly extending part 26a which embraces the part 14a. In the part 14a is provided an opening 27. In the part 26a of the member 26 is stamped a small projection 26b which snaps into the opening 27 when the part 26a is slid into place upon the part 14a, and which yieldingly holds the member 26 in position. The member 26 may be removed easily by simply gripping the part 26a with the fingers and pulling upwardly and yet it dependably holds the shelf member 15 against being accidentally tipped up at the front. A pressure upwardly of the shelf member against the part 26 effects a lever action which causes the part 26a to bind and firmly hold on the part 14a. Thus, if the shelf 15 is accidentally struck from below, it cannot tip and articles carried thereon are not disturbed. When it is desired to remove the shelf member the members 26 are easily slipped out of position as described above.

The bracing rod 16 is secured at its forward end underneath the forward portion of the horizontal bracket arm 14, as shown in Figure 3, preferably by means of a suitable rivet 16b. From the rivet 16b the rod 16 slopes downwardly and rearwardly and is bent to extend horizontally at its threaded portion 16a which, as above described, passes through an opening in the vertical bracket arm 13 and enters one of the keyhole openings in the supporting member 10. As shown in Figure 3, the rear end of the part 16a has formed therein, on the underside thereof, a notch 16c. This notch is adapted to engage with the member 10 at the bottom of the slot, as shown in Figure 3, and it thus holds the bracing rod 16 from direct forward withdrawal, it being necessary to raise the bracing rod at its rear end to disengage the notch before it may be removed. This notch 16c thus holds the bracket member 13-14 against tipping upwardly at the front. If the front portion of the bracing rod 16 or the front portion of the horizontal bracket arm 14 is accidentally struck from below, the action of the notch 16c prevents tipping.

In Figures 7 and 8 there is shown a modification of the construction just described.

In this form the extreme rear end 16d of the bracing rod 16 is flattened and widened after the nut 17 has been threaded into place thereon. This flattened and widened end portion 5 16d is of such width that it will pass through the relatively large part 20 of the keyhole slot, but will not pass through the lower part thereof. When the supporting bracket is placed in position against the member 10, and 10 when the bolt head 19 is inserted through the enlarged portions of its keyhole slot, the part 16d of the bracing rod is inserted through the upper enlarged portion of the keyhole slot positioned to receive it; then the bracket is 15 moved downwardly to bring the bolt head into position with respect to the narrow portion of its slot while, at the same time, the part 16d moves downwardly into the narrow portion of its slot. The part 16d thus locks 20 the lower portion of the supporting bracket against direct forward withdrawal and prevents tipping of the shelf in case the rod 16 or the horizontal arm 14 are struck accidentally from the bottom. When the construction 25 shown in Figures 7 and 8 is employed, the opening in the vertical bracket arm 13 through which the part 16a passes is in the form of a vertical slot. In assembling the device, prior to fastening the member 16 and 30 the bracket member 13—14 together, the nut 17 is threaded into place and the flattened end 16a is then formed on the rod. Thereupon, the flattened end 16d is inserted through the vertical slot in the part 13 and then the member 35 16 is swung through 90° to bring it into the position shown in Figures 7 and 8; thereupon, the forward end of the member 16 is riveted to the part 14 by the rivet 16b, as shown in Figure 3.

40 As many possible embodiments may be made of the above invention and as many changes might be made in the embodiment above set forth, it is to be understood that all matter hereinbefore set forth or shown in 45 the accompanying drawings, is to be interpreted as illustrative and not in a limiting sense.

I claim:

1. In a support for shelves and the like, 50 in combination, a member having therein a slot having a relatively wide portion and a relatively narrow portion, a bracket member having an arm adapted to rest against the surface of said first member, a bolt passing through said arm having a head of a size to permit passage thereof through the relatively wide portion of said slot and to prevent passage thereof through the relatively narrow portion of said slot, the shank of said bolt 55 having an enlarged portion adjacent to said head tapered in the direction of the axis of said bolt and of a size to engage with the sides of said relatively narrow portion of the slot, and a nut on the end of said bolt exterior of said arm for drawing and substan-

tially wedging said enlarged tapered shank portion into said relatively narrow portion of the slot to fasten together said first member and said bracket member.

2. In a support for shelves and the like, in combination, a member having therein a slot having a relatively wide portion and a relatively narrow portion, a bracket member having an arm adapted to rest against the surface of said first member, a bolt passing through said arm having a head of a size to permit passage thereof through the relatively wide portion of said slot and to prevent passage thereof through the relatively narrow portion of said slot, said relatively narrow portion of said slot having a notch in a side wall thereof and the shank of said bolt having an enlarged portion adjacent to said head and adapted to enter said notched part of said slot, and a nut on the end of said bolt exterior of said arm for drawing said enlarged shank portion into said notched part of the slot to fasten together said first member and said bracket member.

3. In a support for shelves and the like, in combination, a member having therein a slot having two relatively wide portions connected by a relatively narrow portion, a bracket member having an arm adapted to rest against the surface of said first member, and a threaded part passing through said arm having a head of a size to permit passage thereof through one of said relatively wide portions of the slot and to prevent passage thereof through the other relatively wide portion and the relatively narrow portion, the major portion of the shank of said threaded part being of a size adapted to permit passage thereof through said relatively narrow portion of the slot and having an enlarged portion adjacent to said head which is adapted to coact with the other relatively wide portion of the slot and is of a size to prevent its passage through the intermediate relatively narrow portion of the slot, whereby, upon the threads of said threaded member being made effective, said threaded part is drawn in a direction to draw said enlarged shank portion into said relatively large slot portion with which it is adapted to coact, said enlarged portion of the shank of said threaded part being tapered and increasing in diameter toward the bolt head thereof, whereby said enlarged portion may be wedged into said relatively wide portion of said slot.

4. In a support for shelves and the like, in combination, a supporting member adapted to be secured against a wall in a vertical position and having therein a plurality of vertically spaced openings, a bracket member having a vertical arm adapted to rest against the surface of said member and an outwardly projecting horizontal arm on which a shelf is adapted to rest, a bolt adjacent the upper end of said vertical arm adapted to take into

one of said openings, a bracing arm extending downwardly and rearwardly from adjacent the outer end of said horizontal arm and passing through said vertical arm adjacent the lower end thereof, the rear end of said bracing arm being adapted to enter another of said openings and having means for engaging with said supporting member about said opening to hold said bracket member 10 against tipping upwardly at the front, and means coacting with said last-mentioned means for clamping therebetween said vertical arm and said supporting member.

5. In a support for shelves and the like, in combination, a supporting member adapted to be secured against a wall in a vertical position and having therein a plurality of vertically spaced keyhole openings, a bracket member having a vertical arm adapted to rest against the surface of said member and an outwardly projecting horizontal arm on which a shelf is adapted to rest, a bolt adjacent the upper end of said vertical arm adapted to take into one of said keyhole openings, a bracing arm extending downwardly and rearwardly from adjacent the outer end of said horizontal arm and passing through said vertical arm adjacent the lower end thereof, and a nut threaded upon said bracing arm 25 forwardly of said vertical arm for adjusting the effective length of said bracing arm and bringing said horizontal arm into proper horizontal position, the rear end of said bracing arm being adapted to enter another of said keyhole openings in said supporting member and being shaped to coact with said keyhole opening in a manner to resist direct forward removal therefrom, said nut serving to clamp said supporting member and 30 said vertical arm between itself and a portion of said bracing arm that coacts with said keyhole opening and that extends to the rear of said supporting member.

6. In a support for shelves and the like, in combination, a supporting member adapted to be secured against a wall in a vertical position and having therein a plurality of vertically spaced keyhole openings, a bracket member having a vertical arm adapted to rest 45 against the surface of said member and an outwardly projecting horizontal arm on which a shelf is adapted to rest, a bolt adjacent the upper end of said vertical arm adapted to take into one of said keyhole openings, a bracing arm extending downwardly and rearwardly from adjacent the outer end of said horizontal arm and passing through said vertical arm adjacent the lower end thereof, the rear end of said bracing arm 50 rearwardly of said vertical arm of the bracket being adapted to enter another of said keyhole openings in said supporting member, said bracing arm having thereon two spaced projecting parts one positioned forwardly of the vertical arm of the bracket to hold the 55

bracing arm against rearward movement and the other positioned rearwardly of the supporting member to hold said bracing arm against forward movement, one of said projecting parts being in the form of a nut threaded upon said bracing arm for clamping said supporting member and said vertical arm between itself and the other projecting part.

7. In a support for shelves and the like, in combination, a supporting member adapted to be secured against a wall in a vertical position and having therein a plurality of vertically spaced keyhole openings, a bracket member having a vertical arm adapted to rest against the surface of said member and an outwardly projecting horizontal arm on which a shelf is adapted to rest, a bolt adjacent the upper end of said vertical arm adapted to take into one of said keyhole openings, a bracing arm extending downwardly and rearwardly from adjacent the outer end of said horizontal arm and passing through said vertical arm adjacent the lower end thereof, the rear end of said bracing arm rearwardly of said vertical arm of the bracket being adapted to enter another of said keyhole openings in said supporting member, said bracing arm having thereon two spaced projecting parts one positioned forwardly of the vertical arm of the bracket to hold the bracing arm against rearward movement and the other positioned rearwardly of the supporting member to hold said bracing arm against forward movement, said last projecting part being at the extreme rear end of said bracing arm and being of a size to prohibit its passage through the relatively narrow portion of the keyhole slot and to permit its passage through the relatively wide portion of the keyhole slots, said keyhole slots having their relatively wide portions above their relatively narrow portions, said bolt and the rear end portion of said bracing arm being adapted to be inserted into their respective keyhole slots in unison and the bracket member being adapted to be then moved downwardly bodily to bring the head of said bolt rearwardly of the relatively narrow portion of its keyhole slot and to bring the rear projecting part of said bracing arm rearwardly of its keyhole slot, one of said projecting parts being in the form of a nut threaded upon said bracing arm for clamping said supporting member and said vertical arm between itself and the other projecting part.

8. In a support for shelves and the like, in combination, a bracket member having a horizontal outwardly extending arm adapted to support a shelf member resting thereon, said bracket member having a recess adjacent its outer end, and means fitted over the end portion of said bracket member and having a part adapted to substantially snap into said

recess, said means having a portion engaging said shelf member to prevent relative movement between said arm and a shelf member resting thereon.

- 8 9. In a support for shelves and the like, in combination, a bracket member having a horizontal outwardly extending arm adapted to support a shelf member resting thereon, said bracket member having a recess adjacent 70 its outer end, the outer end of said arm having an upturned portion to hold the shelf member against sliding forward and said upturned portion having a recess therein, and a sheet metal member having a substantially sleeve-like portion adapted to slide over said upturned portion and having a part adapted to overlap the shelf member resting upon said arm for preventing tilting in an upward direction of said shelf member, said sheet metal 75 member having an inwardly directed portion adapted to be received within said recess for holding said sheet metal member against movement in an upward direction.
- 10 10. In a support for shelves and the like, in combination, a member having therein a slot 80 having a relatively wide portion and a relatively narrow portion, a bracket member having an arm adapted to rest against the surface of said first member, and a threaded member passing through said arm having a head of a size to permit passage thereof through the relatively wide portion of said slot and to prevent passage thereof through the relatively narrow portion of said slot, the 85 shank of said threaded member having a wedge-shaped portion adjacent to said head and of a size to engage with two opposed side portions of said relatively narrow portion of the slot, said wedge-shaped portion extending 90 40 in the direction of the axis of said threaded member, whereby, upon the threads of said threaded member being made effective, said threaded member is drawn in a direction to wedge said wedge-shaped portion of the shank between said two opposed side portions of the slot.

- 11 11. In a support for shelves and the like, in combination, a member having therein a slot having a relatively wide portion and a relatively narrow portion, a bracket member having an arm adapted to rest against the surface of said first member, a bolt passing through said arm having a head of a size to permit passage thereof through the relatively wide portion of said slot and to prevent passage thereof through the relatively narrow portion of said slot, the shank of said bolt having an enlarged portion adjacent to said head and of a size to engage with the sides 110 of said relatively narrow portion of the slot, and a nut on the end of said bolt exterior of said arm for drawing said enlarged shank portion into said relatively narrow portion of the slot to fasten together said first member and said bracket member, said arm having an 115

outwardly bulging portion around said bolt to accommodate said enlarged portion of the shank of the bolt as the nut is tightened up.

- 12 12. In a support for shelves and the like, in combination, a bracket having a horizontal 75 outwardly extending arm adapted to support a shelf member resting thereon, the outer end of said arm having an upturned lip to hold the shelf member against sliding forwardly, a sheet metal member having vertically extending portions shaped to embrace said upturned lip and having another portion extending horizontally to cover over said vertical portions and to overlap the upper surface of the shelf member to hold the latter against 80 tilting upwardly at the front, said vertical portions and said upturned lip telescoping one within the other.

- 13 13. In a support for shelves and the like, in combination, a bracket having a horizontal 85 outwardly extending arm adapted to support a shelf member resting thereon, the outer end of said arm having an upturned lip to hold the shelf member against sliding forwardly, said upturned lip having a recess, and a sheet 90 metal member having vertically extending portions adapted to embrace said lip and a horizontal portion overlapping said vertical portions and overhanging the upper surface of said shelf member to hold the latter against 95 tilting upwardly at the front, said sheet metal member having also a part adapted to substantially snap into said recess.

In testimony whereof I have signed my name to this specification this 28th day of 100 January, 1928.

HENRY F. KEIL.
